SWITCH ASSEMBLY

Donald W. Laviana, Pittsford, N.Y., assignor to General Motors Corporation, Detroit, Mich., a corporation of Delaware

Filed May 24, 1960, Ser. No. 31,372
11 Claims. (Cl. 200—38)

This invention pertains to switches, and particularly to an improved switch assembly of the cam operated type. The present application is a continuation in part of my copending application Serial No. 786,953 filed January 15, 1959.

Heretofore the majority of cam operated sequence switches used in timers for controlling appliances, such as washing machines, have embodied integral leaf spring contact assemblies. In the design of cam operated sequence switches, several factors must be considered, among these being the following: to provide a switch element requiring a minimum torque at its operating cam; to provide a switch element having a high initial contact pressure when it is disengaged from its operating cam and engages one fixed contact; and to require a minimum of additional force to move the switch element into engagement with another fixed contact and provide sufficient contact pressure with a minimum of additional deflection.

The present invention relates to a switch assembly including leaf spring blades, or reeds, having a low force-deflection gradient, the leaf spring blades being prestressed in one direction so as to have two spring rates. Accordingly, among my objects are the provision of an improved leaf spring switch assembly for timers; the further provision of a leaf spring switch assembly having a separate cam follower member attached thereto in such a manner so as to bend the intermediate portion of the leaf spring in the direction of its initial prestressing; the further provision of an improved leaf spring switch assembly of the aforesaid type having a low spring rate in the direction of the prestressing and a high spring rate in the opposite direction; and the further provision of a switch assembly including a leaf spring blade designed to accommodate substantial overtravel without exceeding the yield point of the material and, therefore, avoiding permanent deformation of the leaf spring blade.

The aforementioned and other objects are accomplished in the present invention by prestressing the leaf spring blades adjacent their points of attachment to a base and attaching a saddle member thereto at the intermediate portion of each leaf spring to further prestress each leaf spring in the direction of its initial prestressing. Specifically, the switch assembly includes a base, or terminal block, having a plurality of terminals attached thereto. One end of each leaf spring blade is staked, or otherwise rigidly attached, to a terminal, and the other end of each leaf spring blade carries a contact on each side thereof. One set of the spring blade contacts are engageable with a first set of fixed contacts attached to one set of terminals, and the other set of blade contacts are engageable with a second set of fixed contacts attached to another set of terminals and spaced from the first set of fixed contacts. A saddle member, or harness, is attached to the intermediate portion of each leaf spring blade.

The saddle member is composed of insulating material and comprises a generally rectangular member having a tooth-type cam follower projecting from the upper side thereof. The saddle member is formed with a pair of openings on opposite sides of the projecting cam follower tooth through which a leaf spring blade can be threaded. Each leaf spring blade is formed with a reinforcing bead adjacent the contact end thereof and a circular hole in the medial portion, the circular hole being adapted to re-

2

ceive an integral nub, or stud, formed on the saddle member. The saddle member has transversely extending rails at each end thereof and the integral stud projects downwardly from the lower surface of the cam follower projection. The surface on which the stud is formed is substantially parallel to and spaced above the upper surface of the inner end rail, and the outer end rail is located in a plane spaced above the surface on which the stud is formed such that the leaf spring blade will be bent as it is threaded through the openings and attached to the saddle member. More particularly, the leaf spring blade will be bent in the same direction as its initial prestressing by its attachment to the base.

By bending the intermediate portion of each leaf spring blade, each leaf spring blade is additionally prestressed to obtain the requisite contact pressure between the leaf spring blade contacts and the fixed contacts closest to the cam. The leaf spring blades have low spring rates, or are very limp, when bent in the same direction as the direction of the prestressing, and have high spring rates, or are very stiff, and thus resist bending in the opposite direction. The stiffening bead adjacent the contact end of each leaf spring prevents bending of the leaf springs due to initial prestressing, or preloading, against the fixed contacts closest to the cam. Only a small additional force is required to move the reed into engagement with the fixed contacts spaced farthest from the cam, and after engagement of the leaf spring blades with the latter set of fixed contacts the requisite contact pressure is achieved by bending the spring blades in the direction of their pre-stress, which due to the low spring rate of the blades in this direction, requires a minimum force. This low spring rate enables the switch assembly to accommodate substantial overtravel without exceeding the yield point of the spring blade material and thus avoids permanent deformation.

While the embodiment of the invention as herein disclosed constitutes a preferred form, it is to be understood that other forms might be adopted.

In the drawing:

FIGURE 1 is a plan view of a switch assembly constructed according to the present invention.

FIGURE 2 is a sectional view taken along lines 2—2 of FIGURE 1 showing a segment of an actuating cam with the leaf spring blade engaging a fixed contact closest to the cam.

FIGURE 3 is a view similar to FIGURE 2 showing the leaf spring blade engaging the fixed contact farthest from the cam.

FIGURE 4 is a perspective view of the novel cam follower member, or saddle.

With particular reference to FIGURES 1 through 3, the switch assembly includes a base, or terminal block, 10 of insulating material having spaced sets of spade-type terminals 12, 14 and 16 molded therein. The sets of terminals 12, 14 and 16 project from both sides of the base 10 and have staking lugs 18 located on the upper side of the base. As depicted in FIGURES 2 and 3, a set of substantially S-shaped Phosphor bronze strips 20 are staked to the set of terminals 14, and a second set of substantially S-shaped Phosphor bronze strips 22 are staked to the set of terminals 16. The strips 20 carry fixed contacts 24 which are located in a plane inclined to the base 10, and the strips 22 carry fixed contacts 26 which are located in a plane substantially parallel to and spaced from the plane of the contacts 24.

The switch assembly also includes a plurality of Phosphor bronze leaf spring blades, or reeds, 28. The inner end of each leaf spring blade is staked to one of the terminals 12 and is transversely bent along a line indicated generally by the numeral 30 so that the outer end of each leaf spring blade is prestressed, or preloaded,

towards the fixed contact 26. The outer end of each leaf spring blade carries contacts 32 and 34 on opposite sides thereof engageable respectively with fixed contacts 24 and 26.

The intermediate portion of each leaf spring blade 28 has a circular hole 36 formed therein. A saddle member, or harness, 38, such as depicted in FIGURE 4, is assembled with each leaf spring blade and is attached to the medial portion thereof. The saddle members 38 are composed of insulating material, such as a phenolic condensation product, and comprise side rails 40 and 42, end rails 44 and 46, and an intermediate web 48 having an upstanding toothed-type cam follower 50. A generally rectangular opening 52 is formed between the web 48 and end rail 44, and a second generally rectangular opening 54 is formed between the cam follower tooth 50 and the end rail 46.

As seen particularly in FIGURES 2 and 3, the upper surface 56 of the end rail 44 and a portion 58 of the lower surface of web 48 lie in substantially parallel planes with the portion 58 spaced above the surface 56. The end rail 44 is formed with a chamfered inner edge 60, and the portion 58 of the lower surface of the web 48 is formed with an integral downwardly projecting nub, or stud, 62. The lower surface 64 of the cam follower tooth 50 is inclined upwardly with respect to the lower surfaces of the side rails 40 and 42. The upper surface 66 of end rail 46 is located in a plane substantially parallel to but spaced above both the upper surface 56 of the end rail 44 and the lower surface 50 of the web 48. The inner edge of end rail 46 is formed with a chamfered portion 68, which extends in a direction opposite to the chamfered edge 60.

The saddle member 38 is assembled with the leaf spring blade 28 by threading the inner end thereof through the opening 54 and through the opening 52 prior to attachment of the inner end to the terminal 12. When the stud 62 is aligned with the circular hole 36 in the leaf spring, the diameter of the stud being substantially the same as the diameter of the opening 36, the saddle member 38 will be securely attached to the leaf spring blade 28. In threading the leaf spring blade through the openings 54 and 52, the lower surface of the leaf spring blade engages the upper surfaces 56 and 66 of the end rails 44 and 46 respectively, and the lower surface portion 58 of the web 48, whereby the medial portion of the leaf spring blade will be bent intermediate its ends in the same direction as the prestressing bend 30.

As seen particularly in FIGURES 1 through 3, each leaf spring blade is formed with a reinforcing bead 70 adjacent its outer end. The reinforcing beads 70 stiffen the leaf spring blades in the direction of the prestress and prevent deflection of each leaf spring blade 28 due to engagement with the fixed contact 34.

The cam follower tooth 50 is adapted to be engaged by a rotating cam 72, a fragmentary portion of which is depicted in FIGURES 2 and 3. The cam 72 may include a plurality of rises 74 and dwells 76 such that when the follower 50 engages a rise 74 the leaf spring blade 28 will be moved into engagement with fixed contact 24, and when the follower 50 is aligned with a dwell 76 the leaf spring blade 28 will engage the fixed contact 26. When the follower 50 engages a portion of the cam 72 between the rise 74 and the dwell 76, the contacts carried by the leaf spring blade will engage neither contact 24 nor contact 26. The leaf spring blades 28 are prestressed or preloaded in a direction to engage the fixed contacts 26 which, as clearly seen in the drawing, are located closest to the cam 72. The fixed contacts 24, on the other hand, are located farthest from the cam 72.

The leaf spring blades 28 have, in effect, two spring rates, by virtue of the prestressing by the bend 30 and the intermediate bend by the saddle member 38. In other words, the leaf spring blades 28 have a low spring rate, or are easily flexed, in the direction of the prestress, that is towards the fixed contacts 26 which are closest to

the cam 72. However, the leaf spring blades have a high spring rate, or are very stiff, and thus resist bending in the opposite direction. In this manner, the high contact reaction force when the switch blade contacts 34 engage the fixed contacts 26 will result in very little bending of the switch blades, and high contact pressure can be obtained between the switch blade contacts 32 and the fixed contacts 24 with very little additional deflection of the switch blades. The contact pressure at fixed contacts 26 is the force required to move the switch blades from their free deflected position, caused by prestressing at the bend 30 and the intermediate bend by saddle members 38, to the position of engagement with the fixed contacts 26. The contact pressure at the fixed contacts 24 is the force necessary to bend the spring blades to their final curvature supported at their attachments to the base, the contacts 24, and the surface 58 of the saddle member 38. It is pointed out that the leaf spring blades are disengaged from the surface 66 of the saddle member only during overtravel when the contacts 32 engage fixed contacts 24. The leaf spring blade engages the surface 66 of the saddle member when the spring blade is suspended between the contacts 24 and 26 as well as when the contact 34 engages fixed contact 26.

During rotation of the cam 72 in the direction of the arrow in FIGURE 2, the cam follower 50 will be engaged by the cam surface so as to move the leaf spring blade 28 towards the base 10 and disengage leaf spring contact 34 from fixed contact 26. At this time the leaf spring blade is suspended between the fixed contacts 26 and 24 while constrained within the saddle member 38. When the cam follower 50 engages the rise 74 on the cam 72, the contact 32 will engage the fixed contact 24. Only a minimum force is required to move the switch blade from engagement with contact 26 to engagement with contact 24. After engagement of leaf spring contact 32 with fixed contact 24 the requisite contact pressure is obtained by bending the medial portion of the leaf spring blade 28 in the direction of its prestress as seen in FIGURE 3. Since the spring blade 28 has a low spring rate in this direction, it requires very little additional force to obtain the requisite contact pressure between the leaf spring blade contact 32 and the fixed contact 24. By enabling the leaf spring blade 28 to bend intermediate its ends and become disengaged from the upper surface 66 of the end rail 46, overtravel can be accommodated without stressing the spring blade beyond its elastic limit thereby avoiding permanent deformation.

While the embodiment of the invention as herein disclosed constitutes a preferred form, it is to be understood that other forms might be adopted.

What is claimed is as follows:

1. A cam operated switch including, a base, a leaf spring having one end attached to said base and prestressed adjacent its attachment in one direction, and a member attached to said leaf spring so as to bend the medial portion thereof in said one direction whereby said leaf spring has a low spring rate in said one direction and a high spring rate in the opposite direction.

2. A cam operated switch including, a base, a fixed contact supported on said base in spaced relation thereto, a leaf spring having one end attached to said base and prestressed adjacent its attachment towards said fixed contact, and a member attached to said leaf spring so as to bend the medial portion thereof towards said fixed contact whereby said leaf spring has a low spring rate in the direction of said prestressing and a high spring rate in the opposite direction.

3. A cam operated switch including, a base, a fixed contact attached to said base in spaced relation thereto, a leaf spring having one end attached to said base and prestressed adjacent its attachment in a direction away from said fixed contact, and a member attached to said leaf spring so as to bend the medial portion thereof in a direction away from said fixed contact whereby said leaf spring has a low spring rate in the direction away

from said fixed contact and a high spring rate in a direction towards said fixed contact.

4. A cam operated switch including, a base, first and second fixed contacts attached to said base in spaced relation thereto and in spaced relation from each other, a leaf spring having one end attached to said base and prestressed adjacent its attachment towards one of said fixed contacts, the other end of said leaf spring being disposed between said fixed contacts, and a member attached to said leaf spring so as to bend the medial portion thereof in the direction towards said one fixed contact whereby said leaf spring has a low spring rate in the direction of said one fixed contact and a high spring rate in the opposite direction.

5. The cam operated switch set forth in claim 4 including a cam engageable with said member for moving said leaf spring in the opposite direction into engagement with said other fixed contact, the arrangement being such that when said leaf spring engages said other fixed contact said leaf spring is deflected in the direction towards said one fixed contact.

6. A cam operated switch including, a base, a leaf spring having one end attached to said base and prestressed adjacent its attachment in one direction, said leaf spring having a reinforcing bead adjacent its other end, and a member attached to said leaf spring so as to bend the medial portion thereof in said one direction whereby said leaf spring has a low spring rate in said one direction and a high spring rate in the opposite direction.

7. A cam operated switch including, a base, a fixed contact supported on said base in spaced relationship thereto, a leaf spring having one end attached to said base and prestressed adjacent its attachment towards said

fixed contact, and a saddle member having end rails, an intermediate web and spaced openings between said web and said end rails, said leaf spring being threaded through said openings so as to bend the medial portion thereof towards said fixed contact whereby said leaf spring has a low spring rate in the direction of said prestressing and a high spring rate in the opposite direction, said leaf spring having a reinforcing bead adjacent its outer end for preventing deflection of said leaf spring due to engagement with said fixed contact.

5 10 8. The switch assembly set forth in claim 7 wherein said leaf spring has a circular hole in the medial portion thereof.

15 9. The switch assembly set forth in claim 8 wherein said saddle member is formed with a projecting stud on said intermediate web, and wherein said stud extends through the circular hole in said leaf spring.

20 10. The switch assembly set forth in claim 7 wherein the lower surface of said leaf spring normally engages the upper surfaces of said end rails, wherein the upper surface of said leaf spring engages the lower surface of said intermediate web, and wherein the upper surfaces of said end rails and the lower surface of said web are located in spaced parallel planes.

25 11. The switch assembly set forth in claim 10 wherein the inner edges of said end rails are chamfered in opposite directions.
